UNITED STATES PATENT OFFICE.

STEVEN KOBZY, OF CHICAGO, ILLINOIS, ASSIGNOR TO CHICAGO DIE & SPECIALTY COMPANY, A CORPORATION OF ILLINOIS.

ELECTRIC SWITCH.

Application filed January 5, 1920. Serial No. 349,429.

To all whom it may concern:

Be it known that I, STEVEN KOBZY, a former subject of the Emperor of Hungary (who have declared my intention of becoming a citizen of the United States), and a resident of the city of Chicago, county of Cook, and State of Illinois, have invented certain new and useful Improvements in Electric Switches, of which the following is 10 a specification.

My invention relates to improvements in electric switches, and has for its object the provision of an improved construction of this character, whereby one switch may be 15 readily utilized for controlling a plurality of electric circuits.

Other objects will appear hereinafter.

The invention consists in the combinations and arrangements of parts hereinafter 20 described and claimed.

The invention will be best understood by reference to the accompanying drawings forming a part of this specification, and in which—

25 Fig. 1, is a side view of an electric switch embodying the invention and shown in position of use.

Fig. 2, a top plan view of the same shown partially in section,

30 Fig. 3, an enlarged top plan view of a switch detached and with the enclosing casing removed, and

Fig. 4, a longitudinal section of said switch.

35 The preferred form of construction, as illustrated in the drawings, comprises a suitable base block 5 of insulating material and having a casing 6 of sheet metal fitted and secured thereto. The casing 6 is provided at each side with perforated ears 7, secured to a supporting bracket 8, which in turn is secured to the steering post 9 of an automobile, said bracket carrying a contact screw 10 by means of which the same is 40 electrically connected or grounded on said steering post, as best indicated in Fig. 2.

A vertical metallic post or stem 11 is swiveled centrally on the base 5 and is provided at its bottom with a head 12 engaging 45 against the under side of a metallic contact plate 13 secured in the bottom of block 5, said plate being perforated to permit of the free passage of said stem. The plate 13 is in turn connected with a binding post 14, 50 to which an electric feed wire 15 is connect-

ed for supplying current through said switch. A metallic switch arm or plate 16 is pivotally connected with the upper end of the stem 11, said stem being bifurcated for the purpose and a cotter pin being passed 60 horizontally through said stem and switch arm as shown. A bearing washer 17 is slidably mounted on the stem 11 and a compression spring 18 is imprisoned between said washer and the base block 5, said 65 spring serving to hold said switch arm 16 normally elevated and at the same time insuring good electrical contact between said stem and the plate 13. At its outer end the switch arm 16 is provided with a handle 19 of insulating material operating through a substantially T-shaped slot 20 in the wall of the casing 6, and whereby the switch arm 16 may be readily swung vertically or laterally from side to side.

70 A metallic contact plate 21 is arranged within the casing 6 on top of the base 5 and is provided with a suitable binding post 21' to which is connected a lead wire 22 for supplying current to an electrical appliance, such as the tail light of an automobile. The plate 21 carries a spring leaf contact 23 positioned under the central position of the switch arm 16 and cooperating with a companion spring leaf contact 24 on a metallic 75 plate 25 secured to the base 5, as shown. The plate 25 is provided with a binding post 26 to which a lead wire 27 is connected and which leads to an electrical appliance such as an arm of a signal for an automobile. By this arrangement, it will be observed that depression of the switch arm 16, when in central position, will cause said switch arm to pass between and become frictionally engaged and held by the spring 80 contacts 23 and 24, thus closing the circuits and supplying current through the wires 22 and 27.

75 A metallic spring contact leaf 28 is also mounted on the base 5 in electrical connection with the binding post 21 and in position to operatively engage the base of a signal light 29 mounted in a suitable socket in the top of the casing 6, said light being grounded through said casing in the usual way and 85 whereby when the current is supplied to the contact 21 in any way, the light 29 will be operated to indicate to the driver of the automobile that the switch is in proper working order and also to enable him to see that 90

95 100 105 110

the switch has been properly manipulated. Another metallic plate 30 is also electrically connected with the contact 21, said plate 30 being provided with laterally branching leaf contact arms 31 and 32, positioned, as shown, on opposite sides of the central position of the switch arm 16. Co-operating with the leaf contact 31 is a leaf contact 33 having a binding post 34, to which is connected a lead wire 35 leading to an electrical appliance such as another of the signal arms of the automobile. Co-operating with the other contact 32 is a leaf contact 36 provided with a binding post 37 to which is connected a leaf wire 38 leading to another electrical appliance such as a signal arm of an automobile. The arrangement is such that when the switch arm 16 is swung laterally to one side or the other, it passes between the contacts 31 and 33 or the contacts 32 and 36 and is held thereby, thus placing one pair or the other of said contacts in electrical connection with the switch arm 16 and consequently with the feed wire 15. In either position of the switch arm, current will be supplied to the corresponding lead wire 35 or 38 as the case may be and also to lead wire 22 and the light 29. It will thus be seen that in either of the three operative positions of the switch arm, the lead wire 22 and the light 29 will be supplied with current concurrently with the lead wires 27, 35 and 38, as the case may be. In this way, the various circuits adapted for operation of a signal at the rear of an automobile may be conveniently and efficiently controlled by the manipulation of a single switch which is of simple construction and capable of economical production.

40 While I have illustrated and described the preferred form of construction for carrying my invention into effect, this is capable of variation and modification without departing from the spirit of the invention. I therefore, do not wish to be limited to the precise details of the construction set forth, but desire to avail myself of such va-

riations and modifications as come within the scope of the appended claims.

Having described my invention, what I claim as new and desire to secure by Letters Patent is:

1. An electric switch comprising a base; a stem swivelled in said base; a switch arm pivotally connected with said stem; a bearing washer slidable on said stem and operating against said switch arm; a compression spring imprisoned between said bearing washer and said base and arranged to hold said switch in open circuit position; and electric contacts arranged to be engaged by lateral and vertical swinging of said switch arm, substantially as described. 55

2. An electric switch comprising a base of insulating material; a casing secured to said base; a vertical metallic stem swiveled in said base; a binding post having electrical connection with said stem; a metallic switch arm pivotally connected with the upper end of said stem, said stem being bifurcated and 70 said switch arm being pivoted on a horizontal axis in said bifurcation; a bearing washer slidable on said stem and bearing against the under side of said switch arm; a compression spring imprisoned between said bearing washer and said base; a handle of insulating material on the outer end of said switch arm, there being a substantially T-shaped slot in said casing, through which said handle projects; central contacts arranged to be engaged by depression of said switch arm, when in central position; and lateral contacts arranged on each side of said central position arranged to be engaged by the lateral swinging of said switch arm, 85 substantially as described. 75

In testimony whereof I have signed my name to this specification in the presence of two subscribing witnesses.

STEVEN KOBZY.
